BOARD FOR A COMBINED DART AND
PINBALL GAMEBernard J. Cagan, Torrance, Calif., assignor to Placo
Products Company, Torrance, Calif.

Filed Mar. 7, 1973, Ser. No. 338,648

Term of patent 14 years

Int. Cl. D21—01

U.S. Cl. D34—5 LL

FIG. 1.

FIG. 2.

FIG. 3.

FIG. 1 is a front elevational view of a board for a combined dart and pinball game embodying my new design;

FIG. 2 is a side elevational view of the same, the opposite side being identical;

FIG. 3 is a top plan view of the same.

The back of the board is plain and unornamented.

I claim:

The ornamental design for a board for a combined dart and pinball game, substantially as shown and described.
